CIRCULAR LOOM

Frank Corbyn Hale and James Russell Yorke,
Spondon, near Derby, England, assignors to
Celanese Corporation of America, a corpora-
tion of Delaware

Application December 16, 1936, Serial No. 116,072
In Great Britain January 17, 1936

6 Claims. (Cl. 139—13)

This invention relates to improvements in circular looms of the kind in which the shuttles are held in position within the warp shed by means of rotatable vane wheels disposed so as to pass through one warp sheet into contact with flanged rollers carried by the shuttle, as described, for example, in U. S. Patent No. 2,050,328. The engagement of the vane wheels and the flanges of the rollers provides the thrust on the shuttles necessary to enable relative circular motion to take place between the shuttles and the warps with respect to the loom axis, and the slots in the vane wheels allow for the free passage of the threads of the penetrated sheet during such relative motion.

In a circular loom in which the shuttles rotate about the loom axis, the vane wheels are driven about the axis at the necessary speed, and by their engagement with the flanges of the rollers 20 propel the shuttles at the same angular speed. The vane wheels and the flanged rollers are made of suitable material to stand up to the rolling action between these members, and the rolling contact ensures long working life for the 25 rotating parts and very little tendency to wearing action such as might produce sharp edges liable to damage the warp threads.

According to the present invention, each rotatable roller is provided with a thrust-receiving flange adapted to be engaged by the side of a vane wheel, and a flange of tough resilient material, the resilient flange being disposed adjacent to the side of the thrust-receiving flange which contacts with the vane wheel, and spaced 35 from such side to form an annular groove sufficiently wide to permit free entry therein of the edge of a vane wheel. When the shuttles tend to over-run the vane wheels, as for example when the loom stops, the tough flanges take the thrust 40 of the shuttles on the opposite sides of the vane wheels, instead of the vane wheels coming into contact with hard metallic parts such as might damage them, and especially the rear edges of the vanes.

45 The vane wheels are conveniently mounted in pairs, the two wheels engaging two flanges provided on each roller, and the tough flanges are conveniently disposed one to each roller in front of the rearmost flange so as to contact with the 50 rear face of the foremost vane wheel when overrunning occurs.

Each roller may consist of an assembly of two metal flanges to engage the sides of the two vane wheels, two metallic bushes of lesser diameter 55 to engage the peripheries of the vane wheels,

and a flange of the tough resilient material interposed behind the intermediate metallic bush and adjacent to the front face of the rearmost metallic flange. The tough flange may have the same diameter as the main roller flanges and a 5 length sufficient to give clearance between itself and the foremost metallic flange for the foremost vane wheel.

The resilient flanges are advantageously made of tough, non-metallic material such as fibre or 10 resin-impregnated material such as sheets of canvas or other fabric blocked into a solid mass capable of being machined.

By way of example a form of apparatus according to the invention incorporated in a shuttle of the type described in U. S. Patent No. 2,050,328 will now be described in greater detail with reference to the accompanying drawing in which

Fig. 1 is a front elevation of a shuttle;

Fig. 2 is a front elevation of a detail of Fig. 1 on larger scale; and

Fig. 3 is a part cross-sectional front elevation of a detail of Fig. 2.

Referring to Fig. 1 the shuttle comprises an 25 upper portion 4 on which is mounted a weft spool 5 and a lower or body portion 6, the body portion being formed with an opening 7 across which extend two vertically disposed bearing members 8. The members 8 each hold two double ball bearings 9 (Fig. 3) in two horizontally aligned pairs, each pair rotatably supporting a horizontally disposed spindle 10. The bearing members 8 are spaced apart by members 11 in which the spindles 10 rotate freely. The ends 30 of the spindles 10 project from the bearings 9 and each end supports a flanged roller 12 (Fig. 1), the rollers supported by similar ends of the two spindles being in vertically aligned relation.

Each roller 12 is formed from a number of 40 associated bushes and flanges which fit closely on the spindle 10. Thus each of the two rollers disposed at the left-hand side of the left-hand bearing member 8 comprises a metal bushing 13 (Fig. 3) shaped to fit against the ball bearing 9, a metal flange 14 of larger diameter, a flange 15 of the same diameter of tough resilient material such as fibre or resin-impregnated canvas, a metal bushing 16 of the same diameter as bushing 13 and a further metal flange 17 of the 50 same diameter as flanges 14 and 15. The whole assembly is held in close contact by a washer 18 which is pressed against the end flange 17 by nuts 19 screwing on the threaded end of the spindle 10.

As will be observed from Fig. 3 the general shape of an assembled roller 12 is that of a cylinder formed with an annular groove round its periphery between the flanges 15 and 17, and an 5 end portion of similarly reduced diameter to the right of the flange 14.

In order to drive the shuttles round the loom (i. e. to the left as seen in Fig. 1), each vertical pair of rollers 12 is engaged by an associated pair 10 of vane wheels 21 mounted on a driving shaft 22, the shaft being carried round the loom at the rate at which it is desired to drive the shuttles. The edge of the leading vane wheel 21 of a pair freely enters the groove between the flanges 15, 15 17 and the edge of the other vane wheel fits in the reduced portion of the roller to the right of the flange 14, the peripheries of the wheels rolling against the bushings 13, 16 while the sides of the wheels adjacent to the flanges 14, 17 thrust 20 against the flanges and so urge the shuttle round the loom.

If the shuttles tend to over-run the vane wheels, as for example when the loom stops, the movement of the shuttles relatively to the vane wheels 25 brings each resilient flange 15 into contact with the adjacent side of the nearest vane wheel, the resilient flanges thus taking the thrust of the shuttle. In this manner the danger of the vane wheels contacting with hard metallic portions of 30 the shuttle such as might tend to damage the wheels is obviated.

As will be apparent from Fig. 1 the rollers 12 disposed at the right-hand side of the right-hand bearing member 8, while comprising the same 35 type and number of components as the left-hand rollers, are slightly modified in view of the different "hand" of the rollers. Thus each roller as a whole is disposed nearer to the bearing member 8, the flange 14 abutting the bearing 9 and the bushing 13 being disposed between the flange 17 and the washer 18. Similarly, the resilient flange 15 and the bushing 16 are interchanged, the vane wheel-receiving portions of the roller 40 thus being formed at the right-hand sides of the flanges 14 and 17 as with the rollers 12 disposed at the left-hand side of the left-hand bearing member 8.

Having described our invention, what we desire 50 to secure by Letters Patent is:—

1. Circular loom shuttle of the type which is positioned in the loom by vane wheels, comprising rotatable rollers adapted to be engaged by the vane wheels, each of said rollers being provided with a flange for receiving thrust from the side of a vane wheel and a separate flange of tough 55 resilient fibrous material disposed adjacent to the side of the thrust-receiving flange which contacts with the vane wheel, and spaced from said side to form an annular groove sufficiently wide

to permit free entry therein of the edge of the vane wheel.

2. Circular loom shuttle of the type which is positioned in the loom by vane wheels, comprising rotatable rollers adapted to be engaged by the vane wheels, each of said rollers being provided with a flange for receiving thrust from the side of a vane wheel and a separate flange of resilient resin-impregnated fibrous material disposed adjacent to the side of the thrust-receiving flange 5 which contacts with the vane wheel, and spaced from said side to form an annular groove sufficiently wide to permit free entry therein of the edge of a vane wheel.

3. Circular loom shuttle of the type which is positioned in the loom by vane wheels, comprising rotatable rollers each adapted to be engaged by a pair of vane wheels, a pair of flanges on each roller, each flange being adapted to receive thrust from the side of a vane wheel, and a separate 20 flange of tough resilient fibrous material on each roller, said resilient flange being disposed between the pair of thrust-receiving flanges and spaced from the side of a thrust-receiving flange 25 which contacts with a vane wheel to form an annular groove sufficiently wide to permit free entry therein of the edge of a vane wheel.

4. Circular loom shuttle of the type which is positioned in the loom by vane wheels, comprising composite rollers adapted to be engaged by the 30 vane wheels, each of said rollers comprising a metal flange, a metal bushing of smaller diameter, a tough resilient flange and a further metal flange each having the same diameter as said first-mentioned metal flange, and a further 35 metal bushing having the same diameter as said first-mentioned metal bushing, said flanges and bushings being juxtaposed to form a generally cylindrical body having both a portion of reduced diameter at one end to fit against the periphery of a vane wheel, and an annular groove between a metal flange and the tough resilient flange, the groove being sufficiently wide to permit free entry therein of the edge of a vane 40 wheel.

5. A roller for a circular loom shuttle of the type which is positioned in the loom by vane wheels, comprising a metal thrust-receiving flange and a tough resilient fibrous flange spaced 45 therefrom by means of a metal bushing of smaller diameter than said flanges.

6. A roller for a circular loom shuttle of the type which is positioned in the loom by vane wheels, comprising two metal thrust-receiving flanges and a tough resilient fibrous flange arranged between them and spaced from one of them by means of a metal bushing of smaller 55 diameter than said flanges.
